(57) **CLAIM**

The ornamental design for a tub with lid, as shown and
described.

DESCRIPTION

FIG. 1 is a front elevational view of an embodiment of our
new design comprising a tub with lid, with the rear eleva-
tional view being identical thereto;

FIG. 2 is a bottom plan view of the embodiment of FIG. 1;
FIG. 3 is a top plan view of the embodiment of FIG. 1;
FIG. 4 is a front perspective view of the top and side of the
embodiment of FIG. 1, with the rear perspective view being
identical thereto;

FIG. 5 is an end perspective view of the embodiment of FIG.
1, with the other end perspective view being identical
thereto; and,

FIG. 6 is an end elevational view of the embodiment of FIG.
1, with the other end elevational view being identical
thereto.
